ATTORNEY.

UNITED STATES PATENT OFFICE.

ARTHUR DAVENPORT, OF PHILADELPHIA, PENNSYLVANIA.

DESIGN FOR A TASSEL.

SPECIFICATION forming part of Design No. 22,944, dated December 5, 1893.

Application filed September 1, 1893. Serial No. 484,506. Term of patent 3½ years.

To all whom it may concern:

Be it known that I, ARTHUR DAVENPORT, a citizen of the United States, residing in the city and county of Philadelphia, State of Pennsylvania, have invented and produced a new and original Design for a Tassel, of which the following is a specification, reference being had to the accompanying drawing, forming part thereof.

The leading feature of my design for a tassel is the representation of a tassel-body with pendants, another tassel body with pendants and a cord between the bodies.

In the drawing: A designates the body of a tassel which depends from the cord B.

C designates a tassel body which depends by the cord D from the body A. Said cord D has thereon a head or ball E, which, as will be seen, is between the upper and lower bodies. The tassel bodies consist, each of a head *a* and *b* pendant *b*. 20

What I claim is—

The design for a tassel, substantially as shown and described.

ARTHUR DAVENPORT.
